P. J. GORMAN ET AL

COMBINATION DRAWBOLT AND LOCK FOR TRUNKS

Filed Sept. 17, 1921

WITNESS: *Fred W. Ely*

BY *Victor J. Evans*

ATTORNEY

UNITED STATES PATENT OFFICE.

PATRICK J. GORMAN AND ANTHONY J. PALUMBO, OF BLOOMFIELD, NEW JERSEY.

COMBINATION DRAWBOLT AND LOCK FOR TRUNKS.

Application filed September 17, 1921. Serial No. 501,225.

To all whom it may concern:

Be it known that we, PATRICK J. GORMAN and ANTHONY J. PALUMBO, citizens of the United States, residing at Bloomfield, in the county of Essex and State of New Jersey, have invented new and useful Improvements in Combination Drawbolts and Locks for Trunks, of which the following is a specification.

10 This invention relates to combination draw bolts and locks for trunks.

The principal object is to provide a device of this nature which may serve the triple purpose of a trunk dowel, a draw bolt and means for sealing or locking the trunk when closed.

Another object is to produce a device of this kind in which the trunk engaging portions may be flush with each other so as not 20 to spring the cover away from the body as in similar devices heretofore manufactured.

Another object is to provide a device of this nature which shall be simple of construction, cheap to manufacture, and highly 25 efficient for the purpose for which it is designed.

With these and other objects in view, which will be more apparent as the specification proceeds, the invention resides in 30 certain novel features of construction and combination and arrangement of parts, the essential features of which are hereinafter fully described, are particularly pointed out in the appended claim, and are illustrated 35 in the accompanying drawing, in which:—

Figure 1 is a side elevation of our improved draw bolt and lock in place on a trunk.

Figure 2 is a vertical sectional view of the 40 same.

Figure 3 is a front elevation of the device.

Like characters of reference refer to like parts in all views.

Referring to the drawing in detail, 10 45 represents a plate which is secured to the cover of a ward-robe trunk and which is extruded at 11 so as to offset the dowel, the thickness of the plate 10. The dowel is shown at 12 and is constructed with a hook portion 13 for receiving the tightening bail hereinafter described. The dowel 12 includes the usual tongue 14 to co-act with the receiving portion now to be described.

A plate 15 is secured to the body of the

trunk in any suitable manner and is provided with a housing 16 having an aperture 17 to receive the tongue 14 of the dowel. Mounted pivotally in the opposite end of the housing 17 is a draw lever 18 having a finger piece 19 pierced by an aperture 20. 60 Pivotally mounted in the ears of the member 18 is a draw link or bail 21. A spring 22 secured to member 15 presses against the inner end of member 18 to hold the same in either its locking or unlocking position. 65

A U-shaped tongue 23 is struck up from the member 15 at its lower portion and in line with the aperture 20 so as to protrude therethrough when member 18 is moved to closed position, and tongue 23 may be locked 70 when inserted in aperture 20 by a pad-lock 24, official sealing device, or other securing or sealing instrumentality.

In operation, it is obvious that the tongue 14 will be drawn into the aperture 17 by 75 placing the bail 21 in the hook 13 and then forcing down on the finger piece until the device is in locked position. The offset of the portion 11 and tongue 14 makes the two portions of the trunk come flush together 80 and not unevenly which is a very desirable feature. It will also be seen that there is provided a convenient and efficient means for receiving the official seal or other locking device. 85

While we have described what is deemed to be the most desirable embodiment of our invention, it is obvious that many of the details may be varied without in any way departing from the spirit of our invention, 90 and we therefore do not limit ourselves to the exact details of construction herein set forth nor to anything less than the whole of our invention limited only by the appended claim. 95

What is claimed as new is:—

A trunk fastener comprising super-posed plates, a dowel carried by the upper plate and provided with a depending tongue and a hook portion, a housing carried by the 100 lower plate, a lever pivoted upon the housing and provided with a bail adapted to coact with the hook of the dowel to draw the plates together, the housing co-acting with the tongue to receive the latter when the 105 plates are drawn together, a U-shaped tongue pressed from the lower plate beneath the housing and disposed in a fixed vertical

plane with the tongue of said dowel, and a finger piece carried by the lever below the housing and provided with a vertical slot to permit the U-shaped tongue of said lower plate to pass therethrough and protrude therefrom when the lever is closed, the dowel tongue co-acting with the housing to

secure registration of the slot with said U-shaped tongue when closing the bail against the hook of the dowel.

10

In testimony whereof we have affixed our signatures.

PATRICK J. GORMAN.
ANTHONY J. PALUMBO.
